UNITED STATES PATENT OFFICE.

WESLEY T. CROUSE AND PETER LOUIS MEYER, OF ST. LOUIS, MISSOURI; SAID MEYER
ASSIGNOR TO SAID CROUSE.

PENCIL.

Application filed May 25, 1921. Serial No. 472,324.

To all whom it may concern:

Be it known that we, WESLEY T. CROUSE and PETER LOUIS MEYER, citizens of the United States, and residents of St. Louis, in the county of St. Louis and State of Missouri, have invented a new and Improved Pencil, of which the following is a full, clear, and exact specification.

This invention relates to improvements 10 in pencils, an object of the invention being to provide a pencil which is provided with a novel lead holder, and a novel form of follower for actuating the lead.

Another object is to provide a pencil 15 which is simple in construction, which is arranged to positively prevent clogging of the lead as it is fed through the pencil, which will be strong, durable and efficient in use and comparatively inexpensive to 20 manufacture.

With these and other objects in view, the invention consists in certain novel features of construction, combinations and arrangements of parts, as will be more fully 25 hereinafter described and pointed out in the claims.

In the accompanying drawings—

Figure 1 is a view in longitudinal section through my improved pencil.

Fig. 2 is a view in side elevation with parts broken away for clearness of the follower.

Fig. 3 is a similar view of the cap and screw.

Fig. 4 is an enlarged view in transverse section on the line 4—4 of Fig. 1.

Fig. 5 is a similar view on the line 5—5 of Fig. 1.

Referring in detail to the drawings, 1 represents the casing or barrel of my improved pencil. The barrel is formed in two sections 2 and 3, both of which are internally screw threaded adjacent their meeting ends to receive an externally screw threaded lead holder 4 which fits within the tapered section 3 of the casing.

A follower 5 is provided with a key 6 riding in a longitudinal groove 7 in the casing. The upper end of the follower is 50 hollow and internally screw threaded as indicated at 8 and is slidably freely in the casing, the key 6 serving to prevent rotation thereof.

9 represents a cap which closes the upper

end of the casing 1 and which is removably 55 associated with a hollow screw 10. The cap 9 frictionally grips the upper end of the casing and is rotatable thereabout. The screw 10 fits within the upper end of the follower 5, preferably having screw threaded connection therewith, as shown and is engageable with the follower upon rotation of the cap to feed the same downwardly as will be readily understood. The pusher end 11 of the follower 5 is of a reduced size 60 65 to conveniently fit the bore 12 of the holder 4. It will be noted that when a lead 13 is located in the bore of the holder it is laterally supported on all sides by the holder so that there is no danger of snapping off 70 the lead should the writing end of the pencil become clogged with dust or dirt. Adjacent its lower end the bore 12 is reduced as indicated at 13' and is of the angular 75 cross section indicated in Fig. 5. The reduced portion of the bore forms a shoulder 14, limiting the downward movement of the pusher 11. The angular formation of the lower end of the bore provides a plurality 80 of inwardly presented ribs 15. These inwardly presented ribs dig into the lead 13 as it is propelled toward the writing end of the pencil and cut grooves in the lead. The ribs also serve to positively prevent 85 the lead from falling out of the pencil until the follower 11 has reached the limit of its downward movement.

It will be noted that this particular holder is entirely free from springs, split sleeves and similar devices commonly employed 90 which serve to complicate the operation of the pencil and enhance the chances of clogging the lead. The hollow screw 10 receives a cylindrical container 16 for extra leads, said container being introduced 95 through the open upper end of the screw, and leads may be removed from this container by merely unscrewing the screw 10 from the cap 9 and removing a rubber 17, which for the purpose of convenience in 100 making erasures is fitted within the upper end of the lead container and is normally concealed by the cap 9.

The operation is as follows: The lead may be introduced into the pencil either by pulling the cap 9 and withdrawing the follower and sleeve entirely from the pencil or by unscrewing the lower end 3 of the casing 105 1.

together with the holder 4 and loading the lead directly into the holder. After the pencil has been loaded, turning of the cap 9 to the right will turn the screw 10 and 15 propel the follower 5 downwardly, forcing the lead 13 through the reduced end 13' of the holder. The relatively tight connection between the cap 9 and the upper end of the casing 1 overcomes the tendency of the 20 screw 10 to push the cap upwardly when the cap is turned and thereby assures positive feeding of the lead.

Although we have illustrated one of the preferred embodiments of our invention it 25 will be apparent that various slight changes and alterations might be made in the general form and arrangement of the parts described without departing from the invention and hence we do not wish to limit 30 ourselves to the precise details set forth, but shall consider ourselves at liberty to make such slight changes and alterations as fairly fall within the spirit and scope of the appended claims.

Having thus described our invention, 25 what we claim is:

1. In a lead pencil, a casing having a tapered lower end, a tapered lead holder fitting in the tapered end of the casing and having a longitudinal bore, the lower 30 end of which is polygonal in shape and provided with ribs, and a pusher in the casing for forcing the lead through the holder.

2. In a lead pencil, a casing having a 35 tapered lower end, a tapered lead holder in the tapered end of the casing and having a longitudinal bore, the lower end of which is reduced forming a shoulder and of angular formation, the angular portion 40 of the bore being provided with ribs at the angles thereof, and a pusher in the casing and adapted to enter the bore of the holder to force the lead out through the end of the casing, the movement of the pusher in the 45 holder being limited by the shoulder thereof.

WESLEY T. CROUSE.
PETER LOUIS MEYER.
